US0D1111634S

(12) **United States Design Patent** (10) Patent No.: **US D1,111,634 S**
(45) Date of Patent: ** Feb. 10, 2026

(54) **INDUCTION OVEN RANGE**

(71) Applicant: **LG ELECTRONICS INC.**, Seoul (KR)

(72) Inventors: **Sangwoo Kim**, Seoul (KR); **Sanghun Kim**, Seoul (KR); **Hongsik Kwon**, Seoul (KR); **Hanjin Jung**, Seoul (KR); **Inhwan Ryu**, Seoul (KR)

(73) Assignee: **LG ELECTRONICS INC.**, Seoul (KR)

(**) Term: **15 Years**

(21) Appl. No.: **35/523,641**

(22) Filed: **Jan. 16, 2024**

(80) **Hague Agreement Data**

Int. Filing Date: **Jan. 16, 2024**

Int. Reg. No.: **DM/235378**

Int. Reg. Date: **Jan. 16, 2024**

Int. Reg. Pub. Date: **Jan. 17, 2025**

(30) **Foreign Application Priority Data**

Jul. 25, 2023 (KR) 30-2023-0028780
